UNITED STATES PATENT OFFICE.

HARRISON HURLBERT BOYCE, OF OYSTER BAY, NEW YORK.

DIAPHRAGM SIGNAL-HORN.

1,103,933.

Specification of Letters Patent. Patented July 21, 1914.

Application filed August 8, 1911. Serial No. 342,963.

To all whom it may concern:

Be it known that I, HARRISON H. BOYCE, a citizen of the United States, residing at Oyster Bay, Nassau county, State of New York, have invented certain new and useful Improvements in Diaphragm Signal-Horns, of which the following is a full, clear, and exact description.

My invention relates to signals or alarms for automobiles, boats and the like, and particularly to that type of a horn in which the noise producing element is a rapidly vibrated diaphragm.

The object of the present invention is to provide a simple and effective means for vibrating said diaphragm, as well as to provide in an alarm superior structural details.

In the accompanying drawings Figure 1 is a plan view of the horn complete. Fig. 2 is a rear end elevation. Fig. 3 is in the main a section on the line 3—3. Fig. 4 is an end elevation of certain parts on the plane of the line 4—4, looking in the direction of the arrow.

1 represents a motor arranged within a suitable casing 2, which may be provided with a suitable bracket 3 for securing the instrument to the vehicle.

4 is a diaphragm casing secured to one end of the case 3 in any suitable manner, but preferably arranged eccentric thereto, as shown.

5 represents the front cover, which may carry a horn-like extension 6.

7 is a diaphragm which is properly supported at the front end of the diaphragm casing 4 and which may be held thereto by the cover 5, said parts being clamped together in any suitable way, as by screws 8.

9 is a rotor carried on the shaft of the motor 1, and provided with one or more blades 10, which are pitched generally after the manner of a propeller blade. In the drawings I have shown three of such blades.

11 is a flexible arm mounted at 12 at or near one side of the casing 4.

14 is a hammer carried by the arm 11 and facing approximately the center of the diaphragm 7 at the rear thereof.

50. The arm 11 is preferably made from spring steel, and the hammer normally stands slightly spaced away from the diaphragm aforesaid. The center of the diaphragm may, if desired, be provided with a reinforcing block or anvil facing the ham-

mer 14, which block or anvil, as well as the hammer 14, may be hardened to resist wear.

15 is an oil duct which may be provided, if desired, leading to the rotor 9, which serves to both lubricate the faces of the arms 60 10 as well as the front shaft bearing of the motor 1. The end of the arm 11 projects into the path of movement of the blades 10, and may be suitably shaped to be engaged thereby, whereby the free end of the 65 arm 11 will be pressed back and quickly released so that the spring tension will throw the hammer 14 ahead against the diaphragm 7 to vibrate the latter. The end of the arm 11 may be suitably shaped to best receive 70 the pitched surface of the blades 10, it being preferable to form a slight twist in the end of said arm 11 corresponding generally with the pitch of the blades 10. The blades 10, as well as the end of the arm 11, should 75 preferably be hardened to resist wear.

In operation it is obvious that, as the motor revolves, each blade 10 will contact with the free end of the arm 11, pressing the same back and quickly releasing it so that the 80 hammer 14 will spring forward and strike the diaphragm 7 to vibrate the same. These blows rapidly repeated produce a strikingly effective alarm note, which is prolonged so long as the rotor 9 continues to revolve. 85 The rotor 9 may be driven by any suitable means. In this particular instance I have indicated an electric motor associated with the several parts in such a way as to avoid the necessity of flexible shafts and other 90 connections, although obviously in a broad sense my invention is not restricted to the particular type of driving means employed.

It might be mentioned that it is preferred to locate suitable washers of relatively soft 95 material around the edge of the diaphragm 7 and between the same and the walls of the casing, by which it is gripped.

While I have shown my invention in its preferred form, I appreciate that various 100 modifications and arrangements can be made without departure from the spirit or scope thereof.

What I claim is:

1. In an alarm of the character described, 105 a diaphragm, a holder therefor, a hammer arranged to vibrate said diaphragm, and means for actuating said hammer comprising a rotating element and a pitched blade.

2. In an alarm of the character described, 110

a diaphragm, a holder therefor, a hammer adjacent to said diaphragm but normally free therefrom, and means for vibrating said hammer comprising a rotating element and 5 a pitched blade carried thereby arranged to engage the hammer.

3. In an alarm of the character described, a diaphragm, a hammer adjacent thereto, a spring arm carrying said hammer, and 10 means for vibrating said hammer comprising a rotating element and a pitched blade carried thereby arranged to engage said arm.

4. In an alarm of the character described, a diaphragm, a hammer adjacent thereto, a spring arm carrying said hammer, and 15 means for vibrating said hammer comprising a rotating element and a pitched blade carried thereby arranged to engage said arm close to the hammer.

HARRISON HURLBERT BOYCE.
